UNITED STATES PATENT OFFICE

144,881

DESIGN FOR A CABINET FOR A HEATER OR THE LIKE

Lawrence H. Wilson, Detroit, Mich., assignor to
Motor Wheel Corporation, Lansing, Mich., a
corporation of Michigan

Application December 7, 1944, Serial No. 116,782

Term of patent 14 years

(Cl. D81—19)

To all whom it may concern:

Be it known that I, Lawrence H. Wilson, a citizen of the United States, residing at Detroit, in the county of Wayne and State of Michigan, have invented a new, original, and ornamental Design for a Cabinet for a Heater or the like, of which the following is a specification, reference being had to the accompanying drawings, forming a part thereof.

In the drawings—

Figure 1 is a perspective view of a cabinet for a heater or the like embodying my new design.

Figure 2 is a top plan view of the cabinet.

The side of the cabinet not shown is the same as the side shown. The back of the cabinet is plain.

I claim:

The ornamental design for a cabinet for a heater or the like, as shown and described.

LAWRENCE H. WILSON.
